Primary Examiner — Eric L Goodman*Assistant Examiner* — Darcy E Heflin(74) *Attorney, Agent, or Firm* — Taylor J. Ross(57) **CLAIM**

The ornamental design for a lid for storage container, as shown and described.

DESCRIPTION

This application is related to co-pending Ser. No. 29/603, 953, which is incorporated herein by reference.

FIG. 1 is a top, front and left side perspective view of a lid for a storage container showing my new design;

FIG. 2 is a bottom, front and right side perspective view thereof;

FIG. 3 is a top plan view thereof;

FIG. 4 is a bottom plan view thereof; and,

FIG. 5 is a front elevation view thereof, the rear, right and left sides being identical thereto.
